CLAIM

The ornamental design for a cutting insert, as shown and described.

DESCRIPTION

FIG. 1 is a top plan view of a first embodiment of a cutting insert;

FIG. 2 is a side elevational view thereof;

FIG. 3 is a bottom plan view thereof;

FIG. 4 is an opposite, side elevational view thereof;

FIG. 5 is a top, side perspective view thereof;

FIG. 6 is a back, side elevational view thereof, and;

FIG. 7 is a front, side elevational view thereof.

FIG. 8 is a top plan view of a second embodiment of a cutting insert;

FIG. 9 is a side elevational view thereof;

FIG. 10 is a bottom plan view thereof;

FIG. 11 is an opposite side elevational view thereof;

FIG. 12 is a top, side perspective view thereof;

FIG. 13 is a back, side elevational view thereof, and;

FIG. 14 is a front, side elevational view thereof.

The broken lines show the environment with which the design is associated, are for illustrative purposes only, and form no part of the claimed design or a specified embodiment thereof.
